PROPELLER MOUNTING AND CONTROL
MEANS

Alwin Kost, Portland, Oreg.

Application July 15, 1940, Serial No. 345,584

5 Claims. (Cl. 170—156)

This invention relates to propeller mounting and control means of a type applicable to propellers used in air or water or any like medium.

The present invention utilizes much of the mechanical movement disclosed in my co-pending patent application Serial No. 206,852, filed May 9, 1938.

An object of this invention is to provide adjustable means for mounting a propeller so that the angle of the propeller relative to the object propelled may be varied and to further provide means for adjusting the angle of said propeller.

Propellers on both air and water craft are usually fixedly and non-adjustably secured to driven shafts in a position at right angles to the shaft. When thus mounted the thrust of the propeller is always in the longitudinal direction of the shaft and auxiliary means such as rudders, ailerons or elevators are required to guide the craft. It is an object of this invention to provide a propeller which is adjustable into different angles relative to the axis of the shaft by which it is driven to thereby control the direction of the craft on which it is mounted and make it possible to dispense with the usual guiding or steering devices.

Another object of this invention is to greatly increase the maneuverability and flexibility of an aeroplane and to increase the turning, climbing and diving ability of the same.

A further object is to mount a propeller so that it may be tiltably adjusted on an axis passing through the hub portion of the propeller at substantially right angles to the axis of rotation of the propeller, to provide means for tiltably adjusting said propeller, and to provide means for angularly adjusting the axis on which the propeller is tiltably mounted whereby the propeller may be inclined in any desired position.

Other objects of the invention will be apparent from the following description taken in connection with the accompanying drawings.

In the drawings,

Fig. 1 is a longitudinal vertical section of propeller control and mounting means constructed in accordance with this invention, parts being shown in elevation and a motor being shown diagrammatically.

Fig. 2 is a sectional view with parts in elevation taken substantially on broken line 2—2 of Fig. 1.

Fig. 3 is a sectional view with parts in elevation taken substantially on broken line 3—3 of Fig. 1.

Fig. 4 is a sectional view with parts in elevation and other parts broken away taken substantially on broken line 4—4 of Fig. 1.

Fig. 5 is a fragmentary detached view partly in elevation and partly in section of the propeller supporting means shown in Figs. 1 and 4.

Fig. 6 is a side elevation of the device on a smaller scale than the other figures showing by full and broken lines respectively two inclined positions into which the propeller may be adjusted in operation.

Fig. 7 is an elevation of an indicating device 10 used in connection with my propeller control and mounting means to indicate visually to the operator the position of the propeller.

Fig. 8 is a sectional view of said indicating device taken substantially on broken line 8—8 of Fig. 7.

Fig. 9 is a sectional view, with parts broken away, showing hydraulic control means for an adjustable propeller.

Fig. 10 is a detached elevation of a propeller supporting sleeve shown in Fig. 9.

Like reference numerals designate like parts throughout the several views.

In this application I have disclosed a propeller control and mounting means that is especially well adapted for use on aeroplanes where climbing, diving and turning in all directions is involved but it will be understood that this propeller may also be used as a marine propeller either for submarine vessels or for surface vessels. 30 When the device is used on surface vessels it is not necessary to use the vertical steering means as only horizontal steering is required.

In the drawings, 10 designates a fixed frame of one or more pieces suitably shaped to provide supporting and bearing and housing means for the various parts. A motor 11 is secured to this frame. As this motor 11 may be of any approved type and does not constitute a part of this invention it is shown diagrammatically by dot and dash lines in Figs. 1 and 6. A driven motor shaft 12 is connected with the motor 11 and extends outwardly therefrom to a propeller to be driven.

Three tubular bearing and supporting members 13, 14 and 15 respectively are secured to the frame 10 by cap screws 16 which pass through overlapping base flanges 13', 14' and 15' of the respective members 13, 14 and 15 and are threaded into the frame 10. The tubular members 13, 14 and 15 are of successively larger diameters respectively and are all positioned coaxially of the shaft 12.

The inner tubular member 13 serves as a housing for the shaft 12 and suitable anti-friction bearings 17 for the shaft 12 are provided therein. Thrust on shaft 12 may be taken care of in bear-

ings 17 or at the point of connection with motor 11.

A closely fitting propeller supporting sleeve 18 is rotatably mounted on the inner tubular member 13 and within the medial tubular member 14. This sleeve 18 has a worm gear 19 rigidly secured on its inner end portion, said worm gear being positioned within a housing 20 formed by an enlarged portion of the medial tubular member 14. Forked bracket members 21, Figs. 1, 4, 5 and 6 are provided on the outer end of the sleeve 18 for the purpose of supporting a propeller as hereinafter described.

An externally threaded sleeve 22 is slidably and nonrotatably mounted on the exterior of the medial tubular member 14. A key or spline 23 is operatively disposed between the member 14 and threaded sleeve 22 to prevent relative rotation between these two parts and at the same time allow relative longitudinal movement therebetween.

An internally threaded sleeve nut 24 operatively engages the exterior of the threaded sleeve 22 and is supported within the outer tubular member 15. One end of sleeve nut 24 abuts against a fixed portion of the medial tubular member 14 and the other end of said nut 24 abuts against a shoulder 25 on the end portion of the outer tubular member 15. A worm wheel 26 is rigid with the sleeve nut 24 and positioned within a housing 27 formed within an enlarged portion of the outer tubular member 15.

The outer end portion of the externally threaded sleeve 22 has an externally directed annular flange 22' that fits within an annular notch in a collar 28 and is secured to said collar by a washer plate 30. This connects the collar 28 and the externally threaded sleeve 22, leaving the collar 28 free to rotate relative to the sleeve 22 but making said collar 28 longitudinally movable on the tubular supporting member 14 along with the sleeve 22.

Preferably an extensible tubular guard 39 made of accordion pleated weather proof flexible material has its opposite ends connected by rings 39' to the collar 28 and adjacent end portion of the tubular member 15 respectively. At least one of the rings 39' is freely rotatable on the part to which it is connected so that the collar 28 may rotate relative to the tubular member 15 without damage to the guard 39. The guard 39 excludes all forms of dirt and moisture.

The propeller comprises a recessed hub portion 31 having blades 32 thereon. A bearing support 33 is threaded into the hub 31 and thus rigidly secured to the propeller. Preferably a set screw 29 is used to lock the member 33 to the propeller hub 31. The bearing support 33 is positioned within a bearing comprising an inner race 34 balls 35 an outer race 36 and a supporting ring 37 for the outer race. The supporting ring 37 is provided at diametrically opposite points with outwardly protruding coaxial pins 38 that are pivotally supported in the forked bracket members 21 of the propeller supporting sleeve 18 and provide an adjustable axis about which the propeller is tilted. The axis of pins 38 is transverse to the axis of the shaft 12 and intersects the axis of the shaft 12.

A link member 40 has one end portion connected by a pivot pin 41 with the bearing supporting ring 37 and the other end portion connected by a pivot pin 42 with the collar 28. This link member 40 is preferably positioned at substantially right angles to the axis of the pins 38

38 and serves to tilt or angularly adjust the propeller and to hold the same at any angle at which it is set. Obviously movement of the collar 28 longitudinally of the medial tubular member 14 in either direction will vary the incline or angle of the propeller.

The shaft 12 is connected by universal joint means 43 with the bearing support 33 of the propeller. The universal joint means 43 is positioned substantially co-axially of the pins 38 and provides a drive through which the torque of the shaft 12, when it is driven, is communicated to the propeller irrespective of whether the propeller is positioned at right angles or at an incline to the axis of the shaft 12.

The mechanism for imparting angular movement to the propeller supporting sleeve 18 about its axis comprises a worm 44 meshing with the worm wheel 19, see Fig. 3. The worm 44 is secured on a shaft 45 that is journaled in the tubular member 14. The shaft 45 is connected by bevel gears 46 with an upright shaft 47. Other bevel gears 48 connect the shaft 47 with a horizontal position control shaft 49. Angular movement of the propeller supporting sleeve 18 by rotation of shaft 49 will angularly adjust the position of the bearing supporting ring 37 about the axis of the shaft 12 and this will adjust the angular position of the axis of the pins 38. The collar 28 is free to rotate on flange 22' when link 40 is angularly moved. The position of the axis of the pivot pins 38 will determine the direction in which the propeller will be tilted when the collar 28 is moved longitudinally on the tubular member 14.

Longitudinal movement of sleeve 22 and collar 28 is produced by rotation of sleeve nut 24. The mechanism for rotating sleeve nut 24 comprises a worm 50 meshing with worm wheel 26 and secured on a shaft 51. Worm 50 and shaft 51 are similar to worm 44 and shaft 45 shown in Fig. 3. Bevel gears 52 connect shaft 51 with a vertical shaft 53. Other bevel gears 54 connect the vertical shaft 53 with a horizontal tilt control shaft 55.

The mechanism for actuating the shaft 49 comprises a position control column or steering post 56 having a forked lower end portion 59 and pivoted for oscillation on pivot studs 57, Fig. 2, that are journaled in the frame 10, Figs. 1, 2 and 6. A gear segment 39 on the forked lower end portion of the steering post 56 meshes with a gearwheel 58 on a shaft 60. Bevel gears 61 provide a driving connection between the shaft 60 and the position-control shaft 49. Tilting movement of steering post 56 will impart rotation to shaft 49 and angularly position the propeller supporting sleeve 18.

The mechanism for actuating the tilt control shaft 55 comprises a wheel 62 positioned on the steering post 56 and operatively connected by shaft 63, bevel gears 64, shaft 65, bevel gears 66, shaft 67 and universal joint 68 with the tilt control shaft 55. The tilt control shaft 55 is rotated by the turning of this hand wheel 62 and serves to move the collar 28 longitudinally on the tubular member 14 and tilt the propeller.

The shaft 67 is journaled in a bracket 70 that is rigid with the steering post and the universal joint 68 is positioned substantially on the axis of the pivot studs 57 whereby it will allow tilting of the steering post and at the same time provide a driving connection between shafts 67 and 55.

An indicator to show the amount and direc-

tion of tilt of the propeller is provided. One indicator which may be so used is shown in Figs. 1, 6 and 7 and comprises a housing 71 with a glass face 72 and a dial 73 over which pointers 74 and 75 are movably supported. Pointer 74 is secured to a shaft 76 and pointer 75 is secured to a sleeve 77 positioned on the shaft 76. Bevel gears 78 connect shaft 76 with a shaft 79 and bevel gears 80 connect sleeve 77 with a shaft 81. Shaft 79 is connected by bevel gears 82, Fig. 1, with the position control shaft 49 and shaft 81 is connected by bevel gears 83 with the tilt control shaft 55. Obviously the means connecting the pointers 74 and 75 with the propeller control devices may be varied as long as the pointer 74 is operatively connected with the mechanism for controlling the angular position of the propeller supporting sleeve 18 and the pointer 75 is operatively connected with the means for longitudinally moving the collar 28 to tilt the propeller.

The operation of this propeller mounting and control is as follows: When the collar 28 is moved longitudinally on the tubular member 14 the link 40 will tilt the propeller on the axis of pins 38 and the angular position of the axis of the pins 38 will determine the direction of tilt. When the collar 28 is in the longitudinal position shown in Fig. 1, then the propeller will always be in a plane at right angles to the shaft 12 irrespective of the angular position of said collar 28. If the axis of pins 38 is horizontal and the link 40 is in its lowermost position, that is, directly below the axis of shaft 12 when the airplane or other craft on which the propeller is installed is in an upright position, then outward movement of the collar toward the universal joint 43 will tilt the propeller about a horizontal axis into a climbing position as shown by dot and dash lines in Fig. 6. Inward movement of the collar 28 from the position shown in Fig. 1, will tilt the propeller about the same horizontal axis into a diving position as shown by full lines in Fig. 6. If the propeller supporting sleeve 18 is angularly moved ninety degrees from the position shown in Figs. 1 and 6 then the axis of pins 38 will be vertical and movement of collar 28 along tubular member 14 will incline the propeller sidewise for lateral turning either to the right or to the left, depending on the direction of movement of the collar 28 on the tubular member 14. If the axis of pins 38 is inclined between the horizontal and the vertical then longitudinal movement of the collar 28 in either direction from the position shown in Fig. 1, will tilt the propeller at an angle that will tend to steer the airplane both horizontally and vertically.

Providing for rotary movement of the propeller supporting sleeve 18 through an angle of ninety degrees and for longitudinal movement of the collar 28 in both directions from the position shown in Fig. 1, would make it possible to tilt the propeller into any desired angular position throughout a full three hundred sixty degrees. However I have provided for moving the propeller supporting sleeve 18 through an angle of one hundred eighty degrees, that is through an angle of ninety degrees in either direction from the position shown in Fig. 1, by tilting the steering column either forwardly or rearwardly as shown by dotted lines in Fig. 6, and have provided for obtaining the same angular positioning of the propeller in response to a predetermined amount of movement of the steering wheel 62 in a predetermined direction irrespective of

whether the propeller supporting sleeve is moved through a given angle to the right or to the left from the position shown in Figs. 1 and 6. Obviously satisfactory operation will be provided if the steering post 56 can only be tilted in one direction, that is, either forwardly or rearwardly from the vertical position.

When the steering post 56 is in the vertical position shown by full lines in Figs. 1 and 6, the axis of the pins 38 will be horizontal. With the steering post 56 thus vertically positioned, turning of the steering wheel 62 in one direction will retract the propeller supporting sleeve 18 and incline the propeller as shown by full lines in Fig. 6, while turning the steering wheel 62 in the opposite direction will move the propeller supporting sleeve outwardly and incline the propeller as shown by dot and dash lines in Fig. 6.

If the steering post 56 is inclined either in a forward or a rearward direction from the position shown in Fig. 1, the sleeve 18 will be rotated and the axis of the pins 38 will be angularly moved away from a horizontal position and any tilt imparted to the propeller by the link 40 will be on this non-horizontal axis. If the sleeve 18 is moved far enough to position the axis of the pins 38 vertically then the propeller will be tilted about this vertical axis to provide for horizontal steering only.

The pointer 74 may always indicate on the dial 73 the angular position of the axis of the pins 38 relative to the horizontal. For instance in Fig. 6, this pointer 74 indicates that the axis of pins 38 is oriented ten degrees from the horizontal. The pointer 75 preferably indicates directly the number of degrees of tilt that the propeller is inclined relative to a plane at right angles to the axis of shaft 12.

The collar 28 may be moved longitudinally at any time to vary the tilt of the propeller irrespective of the rotary position of the propeller supporting sleeve 18 and said sleeve 18 may be moved angularly at any time to vary the propeller tilt irrespective of the longitudinal position of the collar 28.

Figs. 9 and 10 show a propeller mounting and control means constructed in accordance with this invention and embodying a hydraulic tilt control.

In these figures 85 is a propeller hub, 86 a bearing supporting ring, 87 a propeller bearing and 88 a universal joint connecting the propeller hub with a driven shaft 89. A propeller supporting sleeve 90 is rotatably mounted on a fixed tubular supporting member 91 that is secured to fixed frame means 92. The forward end of the sleeve 90 has two spaced apart propeller supporting brackets 93, Fig. 10, fixed thereon and pivotally connected with the bearing supporting ring 86 by two pivot pins 94, Fig. 10. The pivot pins 94 and brackets 93 are similar to the pivot pins 38 and brackets 21 shown in Figs. 1, 4 and 6 and function similarly to provide an adjustable axis upon which the propeller 85 can be tilted. Flange means 95 removably secured to the sleeve 90 operates in a suitable groove 96 in the fixed tubular member 91 and prevents longitudinal movement of sleeve 90 but allows said sleeve to be rotatably adjusted.

Angular positioning of the sleeve 90 is controlled by a push and pull rod 96 that is connected with lugs 97 on the sleeve 90. A piston 98 on the rod 96 operates in a hydraulic cylinder 99 to impart movement to the rod 96. Fluid conduits 99 connected with the cylinder 98 provide

for the inlet and exhaust of fluid under pressure from said cylinder to longitudinally move the rod 96. Any suitable fluid pressure supply and control means, not shown, may be connected with the conduits 99' to control the supply of fluid under pressure to the cylinder 98 and angularly position the sleeve 90. The hydraulic cylinder 98 is preferably supported by pivot means 100 connected with a fixed frame 100' whereby a slight swinging movement of this cylinder is provided. Approximately ninety degrees angular movement of the sleeve 90 is preferably provided for.

The bearing supporting ring 86 is pivotally connected, preferably at two diametrically opposite locations, with piston rods 101 that operate in hydraulic cylinders 102 and have cup leathers 103 or like piston means provided on the end portions thereof. The cylinders 102 are supported by pivots 104 that are connected with brackets 105 which are rigid with the sleeve 90 whereby the cylinders 102 and rods 101 move angularly with the sleeve 90.

Fluid pressure conduit means 106 is connected with the rear end portion of each cylinder 102 for the supply and exhaust of fluid under pressure. Suitable fluid pressure supply and control means is connected with the fluid pressure conduit means 106.

Except that the propeller means of Figs. 9 and 10 is controlled by hydraulic instead of mechanical means its operation is similar to the operation of the propeller means shown in Figs. 1 to 8 inclusive and hereinbefore described. Angular movement of the sleeve 90 angularly positions the axis of the pins 94 upon which the propeller is supported and the tilting of the propeller on the axis of pins 94 is controlled by the piston rods 101.

The usual airplane propeller exerts a straight ahead pull on the airplane with which it is connected. To steer such an airplane rudders, elevators, ailerons and the like are ordinarily used to deflect the airplane from the course along which it is being pulled. These steering devices offer resistance to the pull exerted by the propeller. My present invention provides for steering by changing the direction along which the pull is applied and thereby leading the plane in the direction desired. This does away with the necessity of using steering devices which offer resistance to the pull exerted by the propeller.

The foregoing description and accompanying drawings clearly disclose a preferred embodiment of my invention but it will be understood that this disclosure is merely illustrative and that changes may be made within the scope and spirit of the following claims.

I claim:

1. Propeller mounting and control means comprising a bearing supporting ring; a propeller having a hub portion journaled in said bearing supporting ring; a propeller drive shaft; universal joint means connecting said propeller and said drive shaft; means pivotally supporting said bearing supporting ring for tilting movement on an axis transverse to the axis of said propeller drive shaft, said bearing, said universal joint and the pivotal supporting means for said ring all being in a common plane and in substantially the plane of the propeller; and means controlling the tilting movement of said bearing supporting ring on its axis to thereby control the tilt of said propeller for steering purposes.

2. Propeller mounting and control means com-

prising a bearing supporting ring; a propeller having a hub portion journaled in said bearing supporting ring; a propeller drive shaft; a universal joint connecting said propeller and said drive shaft; means pivotally supporting said bearing supporting ring for tilting movement on an axis transverse to the axis of said propeller drive shaft, said bearing, said universal joint and the pivotal supporting means for said ring all being in a common plane and in substantially the plane of the propeller; means controlling the tilting movement of said bearing supporting ring on its axis to thereby control the tilt of said propeller; and means for angularly adjusting the pivotal axis of said bearing supporting ring.

3. Propeller mounting and control means, comprising a propeller drive shaft; a bearing supporting ring positioned substantially coaxially of said propeller drive shaft adjacent one end portion thereof; a propeller having a hub portion journaled in said bearing supporting ring; universal joint means connecting said propeller and said shaft; a rotatably adjustable propeller supporting sleeve mounted coaxially of said drive shaft; means pivotally mounting said bearing supporting ring on said propeller supporting sleeve on a pivotal axis that is transverse to and intersects the axis of said drive shaft, said bearing, said universal joint and the pivotal supporting means for said ring all being in a common plane and in substantially the plane of the propeller; sleeve rotating means connected with said sleeve for angularly adjusting the axis of the pivot means of said bearing supporting ring; and means connected with said bearing supporting ring for angularly adjusting said bearing supporting ring on the axis on which it is supported by said sleeve.

4. Propeller mounting and control means, comprising a propeller drive shaft; a bearing supporting ring positioned substantially coaxially of said propeller drive shaft adjacent one end portion thereof; a propeller having a hub portion journaled in said bearing supporting ring; universal joint means connecting said propeller and said shaft; a rotatably adjustable propeller supporting sleeve mounted coaxially of said drive shaft; means pivotally mounting said bearing supporting ring on said propeller supporting sleeve on a pivotal axis that is transverse to and intersects the axis of said drive shaft, said bearing, said universal joint and the pivotal supporting means for said ring all being in a common plane and in substantially the plane of the propeller; sleeve rotating means connected with said sleeve for angularly adjusting the axis of the pivot means of said bearing supporting ring; a longitudinally movable sleeve; means for longitudinally adjusting said last mentioned sleeve; and a link connecting said last mentioned sleeve with said bearing supporting ring at a point removed from the pivotal axis of said bearing supporting ring for tilting said bearing supporting ring in response to longitudinal movement of said last mentioned sleeve.

5. Propeller mounting and control means, comprising a propeller drive shaft; a bearing supporting ring positioned substantially coaxially of said propeller drive shaft adjacent one end portion thereof; a propeller having a hub portion journaled in said bearing supporting ring; universal joint means connecting said propeller and said shaft; a rotatably adjustable propeller supporting sleeve mounted coaxially of said drive shaft; means pivotally mounting said bearing

supporting ring on said propeller supporting sleeve on a pivotal axis that is transverse to and intersects the axis of said drive shaft; sleeve rotating means connected with said sleeve for angularly adjusting the axis of the pivot means of said bearing supporting ring; a longitudinally movable sleeve; longitudinal adjusting means connected with said longitudinally movable sleeve; a link connecting said longitudinally movable sleeve with said bearing supporting ring

10

at a point removed from the pivotal axis of said bearing supporting ring for tilting said bearing supporting ring in response to longitudinal movement of said longitudinally movable sleeve; and indicator means operatively connected with said sleeve rotating means and with said longitudinal adjusting means and adapted to indicate respectively the direction of tilt and the amount of tilt of said propeller.

ALWIN KOST.
